UNITED STATES PATENT OFFICE.

CHARLES A. DIES, OF CHICAGO, ILLINOIS.

SLICING-MACHINE.

1,344,118.

Specification of Letters Patent. Patented June 22, 1920.

Application filed September 29, 1919. Serial No. 327,061.

To all whom it may concern:

Be it known that I, CHARLES A. DIES, a citizen of the United States of America, and a resident of Chicago, in the county of Cook, State of Illinois, have invented certain new and useful Improvements in Slicing-Machines, of which the following is a specification.

This invention relates to that class of slicing machines in which a knife or cutter blade has a reciprocating movement in actual use, an example of which forms the subject matter of my prior application for Letters Patent, Serial No. 276,473, filed February 12th 1917. And the present improvement has for its objects:

To provide a structural formation and association of parts wherein a short and rapid vibration in a horizontal plane is imparted to the knife or cutter blade during the gradual downward movement of the same through the material undergoing a slicing operation and thus attain a rapid and very effective cutting action.

To provide a simple and efficient means for feeding the material to be sliced with the attainment of uniform regularity in the thickness of the slices produced and in which the feeding mechanism is adapted to be moved down and out of the way, when it is desired to clean the machine parts, all as will hereinafter more fully appear.

In the accompanying drawings:

Figure 1, is a front elevation of a slicing machine embodying the preferred form of the present invention.

Fig. 2, is a plan view of the same.

Fig. 3, is a detail side elevation with parts in section, illustrating the step by step feed mechanism of the machine.

Fig. 4, is a detail longitudinal section illustrating the adjustable carriage of the serrated feed wheel of the machine.

Fig. 5, is a longitudinal section on line 45 5—5. Fig. 1.

Fig. 6, is an enlarged detail section of the cutter blade and its carrier.

Fig. 7, is a detail perspective view of the operating mechanism of the step by step feeding means above referred to.

Like reference numerals indicate like parts in the several views.

Referring to the drawings, 1 designates the material supporting bed plate or base 55 of the machine, provided with the usual fixed side abutment plate or wall 2.

3 designates a guide standard secured to one side of the base 1 in transversely removed relation to the aforesaid abutment wall 2, and preferably of the detail construction set forth in my prior application Serial No. 276,473, and formed with a guide slot or trackway 4 in inclined relation to the horizontal plane of the base 1, with said guide slot comprising an upper and 60 outer angular portion 5 having a greater inclination from a horizontal plane than the lower and inner angular portion 6 of said guide slot, as shown in Fig. 1.

7 designates a transversely arranged cutter carriage of an elongated bar form, provided at one end with a cross-head or stud 8 having sliding engagement with the guide slot or trackway 4 aforesaid. At its other end the carriage 7 is pivotally connected to 75 the upper end of a radius link 9 which is formed with an elongated slot 10 having operative engagement with the driving mechanism of the machine, as follows:

11 designates the primary power shaft of 80 the machine, journaled longitudinally in bearings at the side of the abutment plate or wall 2, and preferably receiving motion through a pair of bevel gears 12 from a transverse countershaft 13 capable of convenient manual rotation.

14 designates a secondary power shaft arranged in parallel relation to the primary shaft 11 and receiving slower speed therefrom through a gear wheel and pinion connection 15 as shown in Figs. 1 and 2.

16 designates a crank disk secured to the secondary shaft 14, and having a crank pin engaging the elongated slot 10 of the radius link 9, and adapted to impart a downward 95 oblique movement to the cutter carriage 7 in actual use, and as set forth in detail in my prior application Serial No. 276,473.

17 designates the cutter blade or knife of the machine, of a straight blade form, and 100 having a guide flange 18 at its back for sliding engagement in a correspondingly formed guide channel in the carriage 7 aforesaid. In the present improvement the cutter blade 17 has a rapid and short stroke reciprocation 105 in the carriage 7 with a view to attain rapid and effective cutting action and to such end has operative connections as follows:

19 designates a sliding head or standard moving in transverse guides 20 on the base 110 1 in adjacent relation to the aforesaid guide standard 3 and provided with a vertical

guide channel for engagement with a pin or stud 21 on the side of the cutter blade 17 to form an operative connection between the parts which permits of an independent vertical movement of the pin or stud 21 in said guide channel in the practical operation of the machine.

22 designates a lever pivoted to the base 1, with one end operatively connected to the 10 sliding head 19 aforesaid, and with the other end connected by a connecting rod 23 with an operating cam mechanism as follows:

24 designates a cam disk fixed on the primary shaft 11 and form with an annular cam 15 groove 25 of a sinuous form, engaging a roller 26 on the end of the aforesaid connecting rod 23 to impart a number of reciprocations to said connecting rod 23, and to the associated sliding head 19 and cutter 20 blade 17, with each revolution of the cam disk.

27 designates an adjustable gage board secured to the base 1 and adapted to maintain the article being sliced in proper position 25 against the side abutment plate or wall 2.

28 designates one or more serrated feed wheels extending up through and a short distance above the top surface of the base 1, 30 through suitable slots therein, and adapted for feeding engagement with the under surface of the material being sliced.

29 designates a carriage or frame hinged at one end to the under side of the base 1 35 and provided with journal bearings for the carrying shaft 30 of the feed wheel 28 aforesaid.

31 designates a spring associated with the carriage 29 and adapted to yieldingly force 40 the same upward and maintain the feed wheel 28 in proper operative position.

32 designates a cam or eccentric mounted on the underside of the base 1 and having engagement with the free end of the carriage 45 29, and adapted to move said carriage downwardly when it is desired to depress the feed wheel 28 below the top surface of the base 1 previous to a cleaning operation on the machine parts. And to such end the carrying 50 shaft of the eccentric 32 is provided with an operating knob or handle 33 for convenient manual operation.

34 designates a ratchet wheel fixed on the carrying shaft 30 of the feed wheel 28, and 55 35 designates a rock arm associated with said shaft and carrying a spring dog or pawl 36 adapted for operative engagement with the ratchet wheel 34 aforesaid.

37 designates an inclined lug formation 60 on the rock arm 35 and located in the path of a corresponding inclined lug formation 38 on the radius link 9 heretofore described, and so that as said radius link 9 nears its vertical position, the lug 38 will contact with 65 the lug 37 to swing the rock arm 35 in one

direction and cause the dog or pawl 36 to engage the ratchet wheel 34 and impart a partial rotation to the same and to the feed wheel 28. Such operation takes place as the radius link 9 nears its vertical position 70 and with the cutter blade 17 in a correspondingly elevated condition to permit a free passage of the material thereunder.

Having thus fully described my said invention what I claim as new and desire to 75 secure by Letters Patent, is:—

1. In a slicing machine, the combination of a base, a cutter carriage arranged transversely of said base, means for imparting oblique movement to said carriage, a cutter 80 blade mounted for reciprocation in said carriage, and means for imparting reciprocation to said cutter blade, substantially as set forth.

2. In a slicing machine, the combination 85 of a base, a cutter carriage arranged transversely of said base, means for imparting oblique movement to said carriage, a cutter blade mounted for reciprocation in said carriage, and means moving in unison with the 90 operating means of said carriage for imparting reciprocation to said cutter blade, substantially as set forth.

3. In a slicing machine, the combination 95 of a base, a cutter carriage formed with a guideway, means for imparting oblique movement to said carriage, a cutter blade 100 formed for sliding engagement in the guideway of said carriage, and means for imparting reciprocation to said cutter blade, substantially as set forth.

4. In a slicing machine, the combination of a base, a cutter carriage formed with a guideway, means for imparting oblique movement to said carriage, a cutter blade 105 110 formed for sliding engagement in the guideway of said carriage, and means moving in unison with the operating means of said carriage for imparting reciprocation to said cutter blade, substantially as set forth.

5. In a slicing machine, the combination 115 of a base provided with an angularly arranged guide plate at one side, a guide standard secured in spaced relation to said guide plate and provided with an oblique trackway, a cutter carriage having guiding engagement at one end with said trackway, a radius link pivotally connected at one end to said carriage and at the other end to said base, means for imparting movement to said 120 radius link, a cutter blade mounted for reciprocation in said carriage, and means for imparting reciprocation to said cutter blade, substantially as set forth.

6. In a slicing machine, the combination 125 of a base provided with an angularly arranged guide plate at one side, a guide standard secured in spaced relation to said guide plate and provided with an oblique trackway, a cutter carriage having guiding 130

- engagement at one end with said trackway, a radius link pivotally connected at one end to said carriage and at the other end to said base, means for imparting movement to said 5 radius link, a cutter blade mounted for reciprocation in said carriage, and moving in unison with the operating means of said carriage for imparting reciprocation to said cutter blade, substantially as set forth.
- 10 7. In a slicing machine, the combination of a base, a cutter carriage arranged transversely of said base, means for imparting oblique movement to said carriage, a cutter blade mounted for reciprocation in said carriage, and means for imparting reciprocation to said cutter blade, the same comprising a revolute shaft carrying a cam disk formed with a sinuous cam groove, and intermediate operative connections between 15 said cam groove and the cutter blade, substantially as set forth.
- 15 8. In a slicing machine, the combination of a base, a cutter carriage arranged transversely of said base, means for imparting oblique movement to said carriage, a cutter blade mounted for reciprocation in said carriage, and means for imparting reciprocation to said cutter blade, the same comprising a revolute shaft carrying a cam disk 20 formed with a sinuous cam groove, an intermediate connecting rod engaging said cam groove, a rock lever engaging said rod, a guide carriage engaging said rock lever and formed with a vertical guideway engaging one end of the aforesaid cutter blade, substantially as set forth.
- 25 9. In a slicing machine, the combination of a base provided with an angularly arranged guide plate at one side, a guide standard secured in spaced relation to said guide plate and provided with an oblique trackway, a cutter carriage having guiding engagement at one end with said trackway, a radius link pivotally connected at one end to said carriage and at the other end to said base, a revolute shaft, a crank disk secured to said shaft and operatively connected to the aforesaid radius link, a cutter blade slidably mounted in the aforesaid carriage, a second revolute shaft geared to the aforesaid revolute shaft and carrying a cam disk 30 formed with a cam groove of a sinuous form, and intermediate operative connections between said cam groove and the cutter blade aforesaid, substantially as set forth.
- 35 10. In a slicing machine, the combination of a base provided with an angularly arranged guide plate at one side, a guide standard secured in spaced relation to said guide plate and provided with an oblique trackway, a cutter carriage having guiding engagement at one end with said trackway, a radius link pivotally connected at one end to said carriage and at the other end to said base, means for imparting movement to said radius link, a cutter blade mounted for reciprocation in said carriage, and means for imparting reciprocation to said cutter blade, the same comprising a revolute shaft carrying a cam disk formed with a sinuous cam groove, and intermediate operative connections between said cam groove, and the like cutter blade, substantially as set forth.
- 40 11. In a slicing machine, the combination of a base provided with an angularly arranged guide plate at one side, a guide standard secured in spaced relation to said guide plate and provided with an oblique trackway, a cutter carriage having guiding engagement at one end with said trackway, a radius link pivotally connected at one end to said carriage and at the other end to said base, a revolute shaft, a crank disk secured to said shaft and operatively connected to the aforesaid radius link, a cutter blade slidably mounted in the aforesaid carriage, a second revolute shaft geared to the aforesaid revolute shaft and carrying a cam disk 45 formed with a cam groove of a sinuous form, an intermediate connecting rod engaging said cam groove, a rock lever engaging said rod, a guide carriage engaging said rock lever and formed with a vertical guideway engaging one end of the aforesaid cutter blade, substantially as set forth.
- 50 12. In a slicing machine, the combination of a base provided with an angularly arranged guide plate at one side, a guide standard secured in spaced relation to said guide plate and provided with an oblique trackway, a cutter carriage having guiding engagement at one end with said trackway, a radius link pivotally connected at one end to said carriage and at the other end to said base, a revolute shaft, a crank disk secured to said shaft and operatively connected to the aforesaid radius link, a cutter blade slidably mounted in the aforesaid carriage, a second revolute shaft geared to the aforesaid revolute shaft and carrying a cam disk 55 formed with a cam groove of a sinuous form, an intermediate connecting rod engaging said cam groove, a rock lever engaging said rod, a guide carriage engaging said rock lever and formed with a vertical guideway engaging one end of the aforesaid cutter blade, substantially as set forth.
- 60 13. In a slicing machine, the combination of a base, a cutter carriage arranged transversely of said base, means for imparting oblique movement to said carriage, the same comprising a radius link pivoted to one end of said carriage and a revolute shaft carrying a crank disk operatively connected to said radius link, a feed wheel projecting through a slot in the main base and having a carrying shaft, and a step by step operating means connecting said link with said carrying shaft, substantially as set forth.
- 65 14. In a slicing machine, the combination of a base, a cutter carriage arranged transversely of said base, means for imparting movement to said carriage, the same comprising a radius link, a cutter blade mounted for reciprocation in said carriage, and means for imparting reciprocation to said cutter blade, the same comprising a revolute shaft carrying a cam disk formed with a sinuous cam groove, an intermediate connecting rod engaging said cam groove, a rock lever engaging said rod, a guide carriage engaging said rock lever and formed with a vertical guideway engaging one end of the aforesaid cutter blade, substantially as set forth.

14. In a slicing machine, the combination of a base, a cutter carriage arranged transversely of said base, means for imparting oblique movement to said carriage, the same comprising a radius link pivoted to one end of said carriage and a revolute shaft carrying a crank disk operatively connected to said radius link, a feed wheel projecting through a slot in the main base and having 10 a carrying shaft, and a step by step operating means connecting said link with said carrying shaft, and comprising an inclined lug on the radius link, a rock arm provided with a companion inclined lug, a ratchet 15 dog carried by said rock arm, and a ratchet wheel carried by the shaft of the feed wheel, substantially as set forth.

15. In a slicing machine, the combination of a base, a cutter carriage arranged trans-

versely of said base, means for imparting 20 oblique movement to said carriage, the same comprising a radius link pivoted to one end of said carriage and a revolute shaft carrying a crank disk operatively connected to said radius link, a feed wheel projecting 25 through a slot in the main base and having a carrying shaft, and a step by step operating means connecting said link with said carrying shaft, a carriage hinged to the under side of the base and having bearings for 30 said carrying shaft, a spring moving said carriage in one direction and an eccentric adapted to move said carriage in the opposite direction, substantially as set forth.

Signed at Chicago, Illinois, this 20th day 35 of September, 1919.

CHARLES A. DIES.
